Primary Examiner—Lisa P. Lichtenstein

CLAIM

The ornamental design for a radiant heat shell which serves as a covering and heat reflector for diesel burners and is part of an airport runway de-icing system, as shown and described.

DESCRIPTION

FIG. 1 is a plan view of the design; FIG. 2 is an enlarged top, end and side perspective view, the opposite side being a mirror image of that shown; FIG. 3 is an enlarged end view, the opposite end being a mirror image of that shown; and, FIG. 4 is a front view. The bottom of the design is flat and unornamented.
